(No Model.)

E. W. VANDUZEN.

STEAM BOILER FURNACE.

No. 278,637.

Patented May 29, 1883.

UNITED STATES PATENT OFFICE.

EZRA W. VANDUZEN, OF NEWPORT, KENTUCKY.

STEAM-BOILER FURNACE.

SPECIFICATION forming part of Letters Patent No. 278,637, dated May 29, 1883.

Application filed December 14, 1882. (No model.)

To all whom it may concern:

Be it known that I, EZRA W. VANDUZEN, a citizen of the United States, and a resident of Newport, in the county of Campbell and State of Kentucky, have invented certain new and useful Improvements in Steam-Boiler Furnaces, of which the following is a specification.

My invention relates to the construction of boiler-furnaces and the prevention of smoke, and particularly to that class employing a blast to feed the air into the furnace-chamber.

In a former patent I have shown and described a transverse air-jet distributor arranged in front of and above the fire for the proper heating of the air before it is delivered onto the incandescent fuel. Experience has shown that such pipes are liable to burn out from being too near the fire, or to bend and warp from too great a heat. My present invention remedies these defects.

Figure 1 is a broken longitudinal sectional elevation of my improvement applied to an ordinary boiler-furnace. Fig. 2 is a top plan view of same. Fig. 3 is a horizontal sectional view of the double injector-nozzle. Fig. 4 is a modified form of the same.

A represents the outer brick wall of a furnace, B the boiler, C the grate-bars and D a supplementary furnace built within an arch, E, as shown in a previous application of mine.

In the device here shown, instead of having the wall of arch E carried up to the boiler, I provide a space, e, above the main portion of the arch, and having a thin brick portion, e', built up to reach the boiler. The space e furnishes additional room for the proper mingling of the combustible gases, and also allows the heat to come into contact with much more boiler-surface.

In order to properly heat the air in the blast-pipes before admitting it into the furnace-chamber, and still not burn up the pipes, I provide one or more transverse distributing pipes or chambers, F F', placed above the door and built in the wall, a representing a series of air-distributing jets or orifices.

G G' represent air-supply pipes, which are brought into the furnace-chamber at or near

the bridge-wall E', thence carried along the furnace-chamber, at a suitable distance above the fuel-supporting grate bars to the front, and thence into the distributing-pipes F F'. These pipes G G' may pass down inside of the brick wall, instead of in front of it, if desired. By extending the pipes G G' along the top and side of the furnace-chamber at a sufficient distance from the fire to prevent being burned or injured, the essential feature of heating the air is still obtained, while the supply of steam is superheated prior to being injected over the incandescent fuel, as more fully hereinafter explained.

Another feature of my invention consists of a T-shaped injector adapted to supply the branch pipes G G'.

H represents the steam-pipe tapping the boiler; I, the air-supply pipe; J, a four-joint union, into which the pipes G G', H, and I respectively tap, L representing the T or double steam-jet, and l l jet-orifices thereof.

N N represent tapering cones entering branch pipes G G'.

Air is supplied through pipe I, and steam through pipe H and orifices l l. Air is driven to the furnace through the branches G G', being largely accelerated by the heating of pipes G G' inside of the furnace-chamber. It is a desideratum to inject into a furnace a minimum amount of steam with heated currents of air, and this result is obtained by the device herein shown.

By connecting the air-pipes G G' with the boiler, as described, and causing them to pass from the rear to the front of the furnace-chamber above the incandescent fuel on the grate-bars, the combined steam and air blast passing through said pipes is superheated in the furnace-chamber before being distributed over the fuel, in such manner that a proper amount of oxygen in a heated condition is supplied to the fire, while a larger volume of air is supplied as compared with the quantity of steam necessary to use, all of which is advantageous in effecting good results in this class of boiler-furnaces.

I am aware that air-distributing pipes have been arranged across the front wall of a furnace-chamber and connected at a point out-

side the furnace with a steam-supply pipe, for introducing combined air and steam to the fuel; but such is not broadly claimed by me.

I claim—

5 In a boiler-furnace, the combination of the transverse distributing-pipe F, branch supply-pipes G G', steam-pipe H, air-pipe I, and double injector L, arranged for operation substantially as described.

In testimony whereof I have hereunto set my hand in the presence of two subscribing witnesses.

EZRA W. VANDUZEN.

Witnesses:

JNO. E. JONES,
JNO. E. WILES.
